UNITED STATES PATENT OFFICE.

GEORGE F. LONG, OF NEW YORK, N. Y., ASSIGNOR TO GOTTFRIED PIEL, OF NEW YORK, N. Y.

AUTOMATIC HORN.

1,226,089.

Specification of Letters Patent. Patented May 15, 1917.

Application filed December 18, 1910. Serial No. 597,677.

To all whom it may concern:

Be it known that I, GEORGE F. LONG, a citizen of the United States, residing in the borough of Manhattan, of the city of New York, in the State of New York, have invented certain new and useful Improvements in Automatic Horns, of which the following is a specification.

My invention relates to horns which are operated by mechanical means, and is especially adapted for use in connection with self-propelled vehicles, boats and under other conditions and circumstances where it is necessary or desirable to give a warning sound.

The various other objects of the invention will be more fully set forth in the following description of one form of mechanism embodying my invention, which consists in the new and novel features of construction and combinations of parts hereinafter set forth and claimed.

In the accompanying drawings:

Figure 1 represents a side elevation of a horn embodying my invention, the casing for the operating mechanism being shown in section to more clearly disclose the construction.

Fig. 2 represents a view on the line 2—2 of Fig. 1.

Fig. 3 represents a section on the line 3—3 of Fig. 1.

Fig. 4 represents a detail view showing the diaphragm.

The horn comprises the bell 1, a vibrating diaphragm 2 and the operating mechanism for producing vibrations of the diaphragm which may be contained in a suitable casing 3. Preferably the diaphragm is secured between flanges 1¹ and 3¹, which are formed integral with the bell and the casing respectively so that it may be under tension. The diaphragm is preferably provided with a plurality of annular corrugations 2¹. An actuating member 5 is secured to the diaphragm preferably centrally thereof, which comprises the plug 6 provided with a central passage 7 having a restricted opening at one end as 8 and tapped at its other end to receive the screw 9.

A wear-piece preferably in the form of a freely rotatable member such as a ball 10 is contained within said passage, which is of slightly less diameter than the passage and rotates therein and also projects through

the opening 8 sufficiently to engage with the grooved surface of a rotating plate or disk 11. Said grooves 12 are arranged radially on said plate or disk, thus providing projecting ribs or flanges 13 which are preferably beveled or wedge shaped in section and of varying width from the center toward the circumference of the disk. If desired both sides of the disk are grooved so as to permit the same to be reversed in case of wear.

The disk is secured to a shaft 14 having a bearing in a bracket 15, secured to the casing. A pinion 16 is provided on said shaft which meshes with the gear 17 upon a parallel shaft 18 mounted in the casing. Said gear is loosely mounted upon the shaft and has one member 19 of a jaw clutch secured to or formed integral therewith, which is normally placed in engagement by means of the spring 20 with the other member 21 of said clutch which is secured to or formed integral with a pinion 22. Said pinion is in mesh with a rack 23 having a knob or button 24 secured thereto whereby the rack may be operated. The rack is normally returned to its original or starting position by a powerful spring 25.

When it is desired to use the horn, the rack, which is normally held in its raised position by the spring 25, is depressed by having suitable pressure applied thereto, and causes the clutch members to engage, thus producing a rotary movement of the disk. As the disk rotates, it contacts with the actuating member secured to the diaphragm, and owing to its uneven surface sets up vibrations in the diaphragm to produce sound. The ball which operates as the contact point for the actuating member, is preferably permitted a slight rolling movement which prevents wear. As soon as the pressure is removed from the rack it is immediately returned to its original or starting position by the spring 25, the arrangement of the clutch members permitting the return movement to be made without rotating the disk.

It is obvious that both the volume and the pitch of the sound can be readily controlled by the depth of the grooves and the width and height of the ribs on the disk, since they determine the extent and rate of the vibration of the diaphragm. If desired the disk may have grooves and ribs of different di-

mensions on opposite sides thereof, so that the character of the sound can be changed by reversing the disk.

Although I have shown one form of mechanism embodying my invention, it is obvious that various changes within the skill of the mechanic may be made in said mechanism without departing from the spirit of the invention provided the means set forth 10 in the following claims be employed.

I claim as my invention:—

1. A horn comprising a metal diaphragm having annular corrugations therein, an actuating member secured to said diaphragm, a movable disk having radial ribs or flanges thereon adapted to engage with said actuating member and vibrate the diaphragm, and means to actuate said disk.
2. A horn comprising a diaphragm under tension, an actuating member secured to said diaphragm comprising a plug and a passage therein with a restricted opening at one end to form a ball seat, a ball in said passage and means for securing said ball in said passage to cause a segment thereof to project beyond the end of the plug, a disk provided with means engaging said projecting segment of said ball to produce to and fro movement of the diaphragm and means 30 for moving said disk.
3. A horn comprising a metal diaphragm under tension having annular grooves therein, an actuating member secured to said diaphragm and comprising a ball rotatable in said member and held against displacement with respect thereto, a disk having radial ribs on its surface to engage with said actuating member, a driving gear for rotating

said disk, a driving pinion, means for actuating said driving pinion, and a clutch 40 mechanism between said pinion and driving gear substantially as described.

4. In a device of the class described, mechanism for actuating a diaphragm horn comprising a diaphragm actuating member formed of a disk provided with diametrically disposed diaphragm contacting ribs and provided with open spaces between adjacent ribs, a shaft supporting said disk centrally thereof, a pinion fixed to said shaft 50 and constituting the end member of a train of gears, a second member of said train meshing with said pinion, a manually actuated reciprocating member and means between said reciprocating member and said second 55 gear train member for converting the reciprocating movement of said handle into continuous rotary movement of said disk, said mechanism being freely rotatable.

5. In a mechanism for actuating a diaphragm horn, a diaphragm engaging member comprising a shaft, a disk mounted on said shaft, one flat surface of said disk being provided with radial grooves to form ribs beveled in section and of varying width, 65 said ribs being spaced apart and adapted to engage a projection from the diaphragm of the horn to vibrate said diaphragm and means for rotating said disk about an axis perpendicular to said grooved face. 70

This specification witnessed this 12th day of Dec. A. D. 1910.
